CLAIM

The ornamental design for a cosmetic bottle with attached applicator, as shown and described.

DESCRIPTION

FIG. 1 is a top perspective view of a cosmetic bottle with attached applicator;

FIG. 2 is a bottom perspective view of the cosmetic bottle and applicator shown in FIG. 1.

FIG. 3 is a front view of the cosmetic bottle and applicator shown in FIG. 1;

FIG. 4 is a rear view of the cosmetic bottle and applicator shown in FIG. 1;

FIG. 5 is a left view of the cosmetic bottle and applicator shown in FIG. 1;

FIG. 6 is a right view of the cosmetic bottle and applicator shown in FIG. 1;

FIG. 7 is a top view of the cosmetic bottle and applicator shown in FIG. 1;

FIG. 8 is a bottom view of the cosmetic bottle and applicator shown in FIG. 1;

FIG. 9 is a top perspective view of the cosmetic bottle shown in FIG. 1 without the applicator;

FIG. 10 is a bottom perspective view of the cosmetic bottle shown in FIG. 9;

FIG. 11 is a front view of the cosmetic bottle shown in FIG. 9;

FIG. 12 is a rear view of the cosmetic bottle shown in FIG. 9;

FIG. 13 is a left view of the cosmetic bottle shown in FIG. 9;

FIG. 14 is a right view of the cosmetic bottle shown in FIG. 9;

FIG. 15 is a top view of the cosmetic bottle shown in FIG. 9;

FIG. 16 is a bottom view of the cosmetic bottle shown in FIG. 9;

FIG. 17 is a front perspective view of the applicator shown in FIG. 1 without the bottle;

FIG. 18 is a rear perspective view of the applicator shown in FIG. 17;

FIG. 19 is a front view of the applicator shown in FIG. 17;

FIG. 20 is a rear view of the applicator shown in FIG. 17;

(Continued)

FIG. 21 is a left view of the applicator shown in FIG. 17;
 FIG. 22 is a right view of the applicator shown in FIG. 17;
 FIG. 23 is a top view of the applicator shown in FIG. 17;
 and,
 FIG. 24 is a bottom view of the applicator shown in FIG. 17.
